UNITED STATES PATENT OFFICE.

RANSAELLER J. JENKS, OF LEWISTON, IDAHO.

AUTOMATIC PRESSURE-GOVERNOR.

1,377,078.

Specification of Letters Patent.

Patented May 3, 1921.

Application filed June 8, 1920. Serial No. 387,399.

To all whom it may concern:

Be it known that I, RANSAELLER J. JENKS, a citizen of the United States, and a resident of Lewiston, in the county of Nez Perce and 5 State of Idaho, have invented a new and useful Automatic Pressure-Governor, of which the following is a specification.

My invention is an automatic governor for use on gas generators wherein a vacuum 10 supply is employed for drawing the gas from the retorts to the hydraulic or service main.

The principal object of the invention is to provide an automatic governor which will prevent excessive vacuum draw on the retorts and at the same time control the gas pressure from the retorts to the hydraulic main.

The invention further provides an automatic pressure governor for gas generators 20 including an automatic governor to be associated with a stand-pipe of a gas retort for controlling the flow of gas from the retort to the service or hydraulic main, and to prevent vacuum draw on the retorts after the 25 fuel charges therein have been spent or partially spent. Thus the retorts of the gas generator may be individually controlled and thereby obviate the necessity of shutting down the entire plant while any one or more 30 of the retorts are being recharged.

Further, the invention provides an automatic governor that will be operated to allow gas to flow into the service main after sufficient gas pressure has been generated and 35 inversely, shall be operated to cut off communication between the service pipe and the retort when the gas pressure has fallen. Thus, gas below a relatively low volatile quality 40 cannot flow into the service main and therefore by lower the quality of gas in the service main.

It is also an object of the invention to provide a gas pressure governor that may be readily installed on the usual dip pipe of the 45 gas generating retort.

The invention further contemplates a gas pressure governor, which is of simple construction and positive in operation.

With the preceding objects and others that 50 may be hereinafter pointed out, the invention consists in the novel combination of elements, construction, operations and specific details to be fully set forth and claimed, the

invention being illustrated in the accompanying drawings, wherein:

Fig. 1 is a fragmentary end elevation of a gas generator having a plurality of retorts, the invention being illustrated in connection with the dip pipe of each retort;

Fig. 2 is a vertical sectional view taken 60 on line 2-2 of Fig. 1, the dotted line illustration showing a modified type of counter-weight;

Fig. 3 is a fragmentary vertical sectional view of one of the dip pipes and the pressure 65 control valve associated therewith;

Fig. 4 is a detailed view of the valve;

Fig. 5 is an elevation of a pipe fitting embodied in the invention;

Fig. 6 is an elevation taken at right angles 70 to Fig. 5;

Fig. 7 is a view partly in vertical cross section and partly in elevation of a modified embodiment of the invention, and

Fig. 8 is a similar view of another modification.

Referring in detail to the drawings wherein like characters of reference designate corresponding parts throughout the several views, the numeral 5 designates a conventional gas generator and includes a plurality of retorts 6, each of which has a vertical stand-pipe 7 leading from one end thereof. The usual hydraulic or service main is designated at 8 and extending into this main 8 is 80 a plurality of dip pipes 9, each of which has communication with one of the stand-pipes 7 by a connection 10. Also communicating with the service main is the usual vacuum conduit which is in communication with any 85 source of vacuum supply (not shown). This structure is one type of gas generator and the parts thereof are referred to and illustrated to illustrate my gas pressure governor, one of which is associated with the dip tube of 90 each retort. Although several retorts and their dip tubes are shown, each is equipped with a governor of identical construction.

The invention, as reduced to practice, consists of a T-fitting 11, the shorter leg of 100 which is of the same diameter as the dip tube and is disposed between the pipe sections forming the dip tube, this leg being longitudinally bulged at one side as designated at 12.

Secured to the flange 13 of a laterally or

vertically disposed nipple 14 formed on the horizontal leg of the T-fitting adjacent its outer end, is the base flange 5 of a vertical pipe 16 which passes centrally through a liquid tank designated at 17. This tank 17 is provided with a removable cover 18 while the outer end of the horizontal leg of the fitting 11 receives a threaded plug 19.

Receiving the vertical pipe 16 and vertically movable in the liquid tank 17 is a pressure actuated bell 20 through which a rod 21 passes and is secured thereto by jam nuts 22 threaded upon this rod at opposite sides of the upper wall of the bell. This rod 21 is vertically movable through the pipe 16 and projects a substantial distance above the cover of the tank 17. A bracket or standard 23 is fixed to the tank 17 to the upper end of which a lever 24 is pivoted at its center, the latter having one end pivotally connected with the upper end of the rod 21 while a rod 24 carrying counterweights 25, is suspended from its opposite end, the counterweights being such as to normally balance the bell 20 as illustrated in Fig. 2.

The lower end of the dip tube is reduced in thickness and affords an annular shoulder 26 which extends at a slight oblique angle with respect to the horizontal, adapted to close this end of the dip tube a valve designated in its entirety at 27. This valve includes a dished or concave bottom 28 merging into an inwardly disposed frusto-conical member 29 at its center. Formed with the bottom 28 at its outer edge is an upstanding annular rim or wall 30 adapted to receive the reduced end of the dip tube when the valve is in closed position. The rim or wall 30 gradually increases in height from one point to a point diametrically opposite and in the same plane as the obliquely disposed annular shoulder; thus a gradual seal or closing of the valve will be effected.

A relatively long stem 31 is rigid with the frusto-conical member 29 and has its upper end pivoted to a horizontally disposed lever 32 adjacent its inner end which is pivoted adjacent its opposite end in bearings 33 extending laterally within the horizontal leg of the fitting 11, this end of the lever being pivoted to the lower end of the rod 21. The inner end of this lever is movable in the depression afforded by the bulged side 12 of the fitting 11.

In operation, the gas generated in the retorts passes up the stand-pipes and into the dip tubes from where it passes into the horizontal leg of the fittings and rises in the bell 20. When sufficient pressure has entered between the water-head and bell to overcome the weighted end of the lever 11 to lower the free end thereof which causes the valve 27 to move away from the end of the dip tube to permit the vacuum in the hydraulic main 65 to draw on the retorts.

Should vacuum from the hydraulic main draw too great on the retort, the bell 20 will be drawn downwardly rocking the lever 32 to move the valve 30 to closed position. This arrangement prevents the vacuum supply from pulling on retorts in which the fuel supply is spent or partially spent. 70

In the modification illustrated in Fig. 7, the valve is operated manually through the medium of a bell crank lever 34 connected with the valve stem, the bell crank being connected with a link 35 having its opposite end pivoted to a lever 36 pivoted at its center and to the ends of which operating cables 37 passing around pulleys 38 are connected. 75

Another modified embodiment of the invention is illustrated in Fig. 8. In this construction, a diaphragm 39 is arranged adjacent one end of the horizontal leg of the fitting 11 and extending through this diaphragm and connected thereto is an operating rod 40, from the outer end of which weights 41 are suspended. The opposite end of the rod 40 is connected to a bell crank lever 42 having operative connection with the valve stem 31. It will be obvious that vacuum from the hydraulic main will move the diaphragm inwardly to rock the bell crank lever, thereby lowering the valve. 90 Upon pressure from the retorts overcoming the vacuum, the diaphragm will be returned to normal position, thereby rocking the bell crank lever to raise the valve. 95

It is to be understood that the forms of my invention herein shown and described are to be taken as preferred examples of the same, and that various changes in the shape, size and arrangement of parts may be resorted to without departing from the spirit 100 of the invention or the scope of the subjoined claims.

Having thus described my invention, what I claim as new and desire to secure and protect by Letters Patent of the United States is:

1. The combination with a gas generator including a plurality of retorts, each having a vertical stand-pipe and a dip tube leading therefrom, and a service main in communication with the dip tube, of a valve normally closing each of the dip tubes, and pressure actuated means for unseating the valves upon pressure reaching a predetermined degree, said means being actuated to move the valves to closed position upon the pressure falling below such predetermined degree. 115

2. The combination with a gas generator including a plurality of retorts, each having a vertical stand-pipe and a dip tube leading therefrom, and a service main in communication with the dip tubes, of a valve slidably mounted upon the lower end of each of the dip tubes and normally closing the same, and a counterbalanced pressure lifted bell 120

operatively connected with each of the valves whereby to move the latter to open position upon pressure reaching a predetermined degree, the bells returning to normal position to move the valve to a closed position upon pressure falling below the predetermined degree.

3. The combination with a conduit having communication with a source of pressure, a valve slidably mounted on one end of the conduit, a bell chamber having communication with the conduit, a normally counterbalanced bell within the bell chamber and having operative connection with the valve whereby to move the valve to open position upon sufficient pressure flowing to the bell chamber to lift the bell.

4. The combination with a conduit having communication with a source of pressure, 20 of a valve adapted to close one end of the conduit, a bell chamber having communication with the conduit and having liquid therein, a counterbalanced bell within the chamber and normally partly submerged in the liquid, an operative connection between the bell and valve to move the same to opened and closed position, the bell returning to its normal position to return the valve to closed position upon pressure falling below a predetermined degree.

5. The combination with a conduit having communication with a source of pressure and service main, of a normally counterbalanced pressure operated bell having communication with the conduit, a valve adapted to control the pressure from the conduit to the service main, and operative connections between the bell and valve whereby to move the valve to open position upon ascent of the bell upon pressure reaching a predetermined degree, and returning the valve to closed position upon pressure falling below such degree to permit the bell to descend.

45 6. The combination with a conduit having communication with a source of pressure and service main, of a normally counterbalanced pressure operated bell having communication with the conduit, a valve normally closing one end of the conduit, a relatively long stem extending therefrom and disposed within the conduit, an operating rod having one end secured to the bell, and a lever having one end pivotally connected with its rod and the opposite end pivotally connected to the valve stem.

7. In a pressure governor, a vertical pipe having communication with a source of pressure, a valve adapted to close one end 60 of the vertical pipe, a horizontally disposed

pipe communicating with the vertical pipe, a vertical pipe leading from one end of the latter, a bell chamber supported on said vertical pipe, a bell within the chamber and overlying said vertical pipe, means normally counterbalancing the bell, an operating rod connected with the bell and passing through said vertical pipe, a lever passing through the horizontal pipe and extending within the first mentioned vertical pipe and having one end pivotally connected with the operating rod, and its opposite end operatively connected with the valve whereupon pressure lifting the bell, the valve will be moved to open position, the bell returning to normal position upon falling of the pressure.

8. In a pressure governor, a vertical conduit having communication with a source of pressure, a valve including a bottom wall 80 concaved and merging into an inwardly disposed frusto-conical member at its center, and an annular rim adapted to receive one end of the pipe when the valve is in closed position, a relatively long stem extending 85 within the conduit and having one end secured to the frusto-conical member, and means operatively connected with the valve stem for moving the valve to open and closed position.

9. The combination with a gas generator including a service main having communication with a source of pressure and a source of vacuum, a bell chamber communicating with the service main, a vertically movable 95 bell mounted therein, and means operated by the bell upon ascent of the same caused by gas pressure therein to permit pressure to flow into the service main; the bell being drawn downwardly to cause such means to 100 be moved to a position to cut off communication between the service main and bell chamber upon exhaustion of pressure from the bell.

10. The combination with a gas apparatus 105 including a retort and service main having communication with a source of vacuum, a stand-pipe communicating with the service main and retort, a dip tube communicating with the service main and stand pipe of a 110 vertically movable valve for closing one end of the dip tube, a bell chamber, a bell mounted therein and operatively connected with the valve and adapted to be raised vertically to open the valve upon sufficient 115 pressure entering beneath the bell, the bell being caused to descend to close the valve upon exhaustion of pressure from the bell.

RANSAILLER J. JENKS.
